CLAIM

The ornamental design for a shower system, as shown and described.

DESCRIPTION

FIG. 1 is a perspective view of a shower system showing our new design;

FIG. 2 is a front elevational view thereof;

FIG. 3 is a rear view thereof;

FIG. 4 is a side view thereof;

FIG. 5 is a top plan view thereof; and,

FIG. 6 is a bottom view thereof.

The broken line showing of portions of the shower system are included for the purpose of illustration and form no part of the claimed design.
